DESIGN FOR A TEXTILE FABRIC OR SIMILAR ARTICLE

Nathan Marcus, New York, N. Y.

Application July 27, 1938, Serial No. 78,765

Term of patent 3½ years

To all whom it may concern:

Be it known that I, Nathan Marcus, a citizen of the United States, residing in the city of New York, county of New York, and State of New York, have invented a new, original, and ornamental Design for a Textile Fabric or Similar Article, of which the following is a specification, reference being had to the accompanying drawing, forming a part thereof.

The figure is a plan view of a textile fabric showing my new design.

The design consists of a series of crimped elements having the configurations of leaf and floral elements superimposed on a background interspersed with rabbit hair yarn, as shown.

I claim:

The ornamental design for a textile fabric or similar article as shown and described.

NATHAN MARCUS.
